Attorney

UNITED STATES PATENT OFFICE.

VOLLIE F. MULKEY, OF PLATTE CITY, MISSOURI.

SPARK PLUG.

Application filed June 9, 1921. Serial No. 476,265.

To all whom it may concern:

Be it known that I, VOLLIE F. MULKEY, a citizen of the United States, residing at Platte City, in the county of Platte and State of Missouri, have invented certain new and useful Improvements in a Spark Plug; and I do hereby declare the following to be a full, clear, and exact description of the invention, such as will enable others skilled in the art to which it appertains to make and use the same.

The invention relates to electric ignition for internal combustion engines and more particularly to a spark plug which provides the spark gap essential to the operation thereof.

The chief object in view is the provision of a spark plug which is practically self cleaning and prevents accumulation of oil or carbon and which maintains clean terminals and insures positive sparking when the current is properly supplied.

Other objects and advantages will be apparent and suggest themselves as the nature of the invention is understood.

While the drawing illustrates an embodiment of the invention it is to be understood that in adapting the same to meet different conditions and requirements, various changes in the form, proportion and minor details of construction may be resorted to without departing from the nature of the invention.

Referring to the accompanying drawing forming a part of the specification,

Figure 1 is a side view of a spark plug illustrative of the invention,

Figure 2 is an elevation thereof partly in section, and

Figure 3 is a horizontal section on the line $x-x$ of Figure 1, the ball terminal being omitted.

Corresponding and like parts are referred to in the following description and designated in the several views of the drawing by like reference characters.

The spark plug illustrated is in general structure of ordinary formation and comprises a shell 1, a nut or gland 2 and a core 3 of insulating material such as porcelain. The positive electrode 4 is mounted in the

core 3 in any preferred way. The lower portion of the shell 1 is externally screw threaded for attachment to the entrance in a manner well understood.

In accordance with the present invention the lower end of the shell 1 is closed and of rounded formation. An opening 5 is formed in the extremity of the closed end and is centrally disposed. Other openings 6 are formed in the sides of the rounded end of the shell and are equally spaced apart. The openings 5 and 6 are practically of uniform size. A metal ball 7 is located within the closed end of the shell 1 and is of such diameter as to prevent its escape through any one of the openings 5 or 6 and at the same time prevent its lodging in any one of said openings to prevent free movement thereof. The ball 7 constitutes the terminal of the negative electrode and the spark gap is formed between said ball 7 and the terminal of the electrode 4. The movement of the ball 7 prevents fouling of the plug and renders the same self cleaning as it prevents any accumulation of oil or carbon. The vibration of the engine, assisted materially by the jolt and jar of the vehicle, and the disturbing action of compression and explosion of the fuel insure movement of the ball terminal 7, whereby any oil or carbon tending to accumulate is dislodged and the terminals kept clean thereby insuring positive sparking when the current is properly supplied to the plug in the operation of the engine.

Having thus described the invention, what I claim is:

A spark plug having its shell continued below the lower end of its positive electrode and rounded and closed, a relatively large ball loose in said closed end and forming the ground terminal of the spark plug, said closed end having a central opening in its lower wall and having equally spaced openings in its side wall, all of said openings being round and having a continued bore and being of less diameter than the diameter of the ball, the openings in the side wall having their upper edges substantially in the plane of the lower end of the positive

electrode and having their central axis above the central axis of the ball when the ball is in normal position, whereby the ball is spaced from the positive electrode and the openings in the side wall are in alignment with the point where the spark will occur.

In testimony whereof I affix my signature in presence of two witnesses.

VOLLIE F. MULKEY.
